UNITED STATES PATENT OFFICE.

ABRAM C. MOTT, JR., OF PHILADELPHIA, PENNSYLVANIA, ASSIGNOR TO ABRAM COX STOVE COMPANY, OF PHILADELPHIA, PENNSYLVANIA, A CORPORATION OF PENNSYLVANIA.

GRATE BAR.

Application filed April 7, 1925. Serial No. 21,394.

One object of this invention is to design a grate bar to be used in furnaces burning coal of small sizes.

A further object of the invention is to reduce the cost of manufacturing grate bars of this type by so designing the bars that they can be cast without the use of cores.

A further object of the invention is to make the grate bars so that the particles of coal cannot pass through the air passage between the ribs of the bars.

In the accompanying drawings:

Fig. 1 is a plan view of my improved grate bar;

Fig. 2 is a side view;

Fig. 3 is a longitudinal sectional view on the line 3—3, Fig. 1;

Fig. 4 is a transverse sectional view on the line 4—4, Fig. 1; and

Fig. 5 is a sectional perspective view, showing one end of a grate bar.

In the drawings, one section is shown. The section can be of any length desired without departing from the invention.

The grate bar 1 consists of a single casting made without the use of cores. The bar has two series of longitudinal ribs 2 and 3, which are spaced apart, as shown. The series of ribs are on different planes. The upper series is located directly over the spaces between the ribs of the lower series. The spaces between the ribs of both series are wider than the ribs to allow for casting without the use of cores.

Two of the ribs of the lower series 3 are much deeper than the intermediate rib, forming strengthening webs 4, which extend from one section 5 to the other end section 1. The upper series of ribs 2 extend over the end sections 5 and are connected to the end sections, as shown in the drawings.

The bar is provided with one or more transverse connecting members 6, which

strengthen the bar and provide firm supports for the upper series of ribs. 45

On referring to the drawings, it will be noticed that the spaces between the upper series of ribs extend uninterruptedly from one end of the bar to the other so that, when the bars are assembled in a furnace, the 50 grate can be readily freed of ashes, the upper series of ribs preventing coal passing through the spaces between the lower ribs.

I claim:

1. A grate bar made of a single casting 55 and having two series of spaced longitudinal ribs on different planes, the lower surfaces of one series being above the upper surfaces of the other series, the ribs of the upper series being above the spaces between the 60 ribs of the lower series; and end sections at the ends of said ribs formed integrally therewith.

2. A grate bar made of a single casting and having two series of spaced longitudinal ribs 65 on different planes, the lower surfaces of one series being above the upper surfaces of the other series, the ribs of the upper series being above the spaces between the ribs of the lower series; end sections at the ends of said 70 ribs formed integrally therewith, and certain of the ribs of the lower series being extended to form deep strengthening webs extending from one end section to the other.

3. A grate bar made of a single casting 75 and having two series of spaced longitudinal ribs on different planes, the lower surfaces of one series being above the upper surfaces of the other series, the ribs of the upper series being above the spaces between the ribs 80 of the lower series; end sections at the ends of said ribs formed integrally therewith, and an intermediate transverse connecting member and deep strengthening webs extending from one end section to the other.

ABRAM C. MOTT, JR.
